UNITED STATES PATENT OFFICE.

AMANDUS JOHANN AUGUST OESTERREICH, OF HAMBURG, GERMANY,
ASSIGNOR TO THE SINGER MANUFACTURING COMPANY, A CORPO-
RATION OF NEW JERSEY.

SEWING-MACHINE HEMMER.

SPECIFICATION forming part of Letters Patent No. 739,210, dated September 15, 1903.

Application filed November 4, 1902. Serial No. 130,110. (No model.)

To all whom it may concern:

Be it known that I, AMANDUS JOHANN AUGUST OESTERREICH, a citizen of the German Empire, residing at Hamburg, Germany, have 5 invented certain new and useful Improvements in Sewing-Machine Hemmers, of which the following is a specification, reference being had therein to the accompanying drawings.

In the use of sewing-machine hemmers 10 making a wide fold or hem for hemstitching it is essential that the work should be guided to the stitch-forming devices with great accuracy, particularly where the hems run across each other, as in the corners of handkerchiefs, 15 table-cloths, &c., and the hemmers heretofore in use could not always be depended on for accurate work.

This invention has for its object to provide a sewing-machine hemmer adapted for making 20 folds or hems of different widths and which will present the goods to the stitching devices smoothly and accurately.

In the accompanying drawings, Figure 1 is a sectional elevation of the improved hemmer 25 in operative relation to parts of a sewing-machine, but with the movable part of the hemmer adjustable laterally for the insertion of the work. Fig. 2 is a sectional view of the hemmer with the parts in working position. 30 Fig. 3 is a plan view of the hemmer and a part of the work-plate of the sewing-machine, showing also the work. Fig. 4 is a side view of the hemmer looking from right of Fig. 1, but with the interchangeable guiding-plate 35 removed. Fig. 5 illustrates a guiding-plate of different width from that shown in Figs. 1, 2, and 3.

Referring to the drawings, *a* denotes part of the depending head of a sewing-machine, 40 and *b* part of the machine work-plate. Attached to the head *a* is an arm *c*, which supports a plate *d*, having an upturned part *e*, by means of which and of a set-screw *f* said plate is adjustably attached to said arm *c*. 45 Secured to the plate *d* is a thin plate *g*, which is supported slightly above the work-plate *h*, and the vertical position of said plate *g* may be changed to accommodate different thicknesses of material passing beneath it by vir-

tue of the slot *h*, through which the set-screw *f* passes, as will be understood.

Mounted on the plate *g* is a block *i*, having a raised tongue *k*, which serves as a guide for the left-hand edge of the hem-fold, and attached to a sliding bar *m*, mounted in ways 55 on the plate *d*, is a cap *n*, which when in the working position (shown by Figs. 2 and 3) embraces the tongue *k*. The sliding bar *m* is provided with a pin *o*, embraced by a forked lever *p*, by which the cap *n* may be adjusted 60 to the different positions shown in Figs. 1 and 2, either for the convenient insertion of the work or for the hemming operation. A detent-spring *q*, attached to the lower face of the lever *p* and having a pointed free end to 65 enter slight indentations *r* in the plate *d*, serves to hold the said lever in the different positions to which it may be moved.

The guiding-plate *s*, which serves to form the right-hand edge of the hem-fold and 70 around which the fabric passing beneath the plate *g* is folded, is removably supported in the said plate *g*. To hold the said guiding-plate *s* in place, said plate is provided with a longitudinal groove *f'*, entered by a friction-spring or spring-tongue *u* beneath the undercut right-hand part of the block *i*. This construction permits a guiding-plate *s* to be removed and another interchangeable guiding-plate of different width to be substituted there- 75 for in making hems of different widths.

In the use of the attachment the cap *n* may be shifted to the left, as shown in Fig. 1, when the work is to be inserted, and is then shifted back to the working position. (Shown 85 in Figs. 2 and 3.) By reference to Fig. 3 it will be seen that the hem-fold in the fabric *x* overlies the guiding-plate *s* and the block *i*, so that the goods are so disposed that when inserting the same in the hemmer the attendant can gently press them into place with the finger instead of being required to use a pointed instrument for this purpose, as with some hemmers heretofore in use, while the construction of the device is such that the 90 hem is guided smoothly and accurately to the stitch-forming devices of the machine.

Having thus described my invention, I

claim and desire to secure by Letters Patent of the United States—

1. A sewing-machine hemmer comprising a tongue, as *k*, for guiding the left-hand edge of the hem-fold, and a removable and interchangeable guiding-plate, as *s*, for the right-hand edge of the fold, combined with a movable cap, as *n*, embracing said tongue, a slide by which said cap is carried, an adjusting-lever *10* for said slide, means for holding said lever in different positions of adjustment, and means for supporting said parts from the head of a sewing-machine and above the work-plate thereof.

2. The combination with the arm *c*, of the plate *d*, adjustably connected therewith, the plate *g* attached to said plate *d* and provided with the block *i* having the guiding-tongue *k*, the movable cap *n*, embracing said tongue, the removable guiding-plate *s*, and means for supporting said parts from the head of a sewing-machine and above the work-plate thereof. *15* *20*

In testimony whereof I affix my signature in presence of two witnesses.

AMANDUS JOHANN AUGUST OESTERREICH.
